UNITED STATES PATENT OFFICE.

HINTON AUSTIN JACKSON, OF CLINTON, INDIANA, ASSIGNOR OF ONE-HALF TO
DUNCAN B. MEDILL, OF CLINTON, INDIANA.

ELECTRIC RAILWAY-SWITCH.

1,102,664.

Specification of Letters Patent.

Patented July 7, 1914.

Application filed March 27, 1914. Serial No. 827,590.

To all whom it may concern:

Be it known that I, HINTON AUSTIN JACKSON, a citizen of the United States of America, residing at Clinton, in the county 5 of Vermilion and State of Indiana, have invented certain new and useful Improvements in Electric Railway-Switches, of which the following is a specification.

The present invention relates to improvements 10 in electric railway switches, designed especially for use in switching mine cars in mines.

The primary object of the invention is to improve the switching mechanism for 15 mine cars, so that the cars may be shunted as desired.

Many automatic switches are now in use 20 on mining railways for shunting cars alternately first on to one track and next on to another track from an incoming track, but with the utilization of my switch and electric apparatus as many cars as are desired can be thrown or shunted from a single incoming track on to either of two outgoing 25 tracks, either alternately, or following on the same track in succession.

The invention consists essentially in the 30 novel combination and arrangements of a single incoming track and a pair of outgoing tracks with their switches, and a single pole double throw electric switch for controlling the switch tongues to open or close the outgoing tracks.

In the accompanying drawings I have 35 illustrated one complete example of the physical embodiment of my invention constructed according to the best mode I have so far devised for the practical application of the principles of the invention.

Figure 1 is a plan view of a portion of a mine railway showing the end of an incoming track and the switches for two outgoing tracks therefrom and the electric control of these parts. Fig. 2 is a side elevation of a 45 portion of a rail showing the contact lever for completing the electric circuit to operate the device. Fig. 3 is an enlarged detail view of a portion of Fig. 1, to more clearly illustrate the construction of the parts.

In the preferred embodiment of my invention 50 I employ the straight incoming track comprising the rails 1-1, and provided with the bumper or bumper block 2 at the end of the track. Both rails of the incoming track are broken as indicated, and the sec-

tions 2'-2' of this track are turned out on divergent lines as at 3-3', and the frog sections 4-4' form the other rails for these two outgoing tracks. For convenience in describing the apparatus I will designate 60 the left outgoing track as 5, and the right outgoing track as 6, and it will be seen that the left outgoing track has a switch tongue 7 pivoted at 8 in line with the frog section 4, and the outgoing track 6 has a switch 65 tongue 9 pivoted at 10 in line with the frog section 4'. In the drawings the switches are arranged so that a car can be shunted from the incoming track to the outgoing track 70 6. The switch tongues 7 and 9 are controlled by the respective electromagnets 11 and 12, each located outside of the track and in position so that its armature 13 and link 14, the latter attached to the switch tongue, are in position to move the switch 75 tongue when either of the electromagnets are energized. These electromagnets are energized by the presence of a mine car, the wheels of which are adapted to ride down a lever arm 15, pivoted at 16 to the side of the 80 rail 2'. In Fig. 2 it will be seen that the longer arm 17 of the lever is of sufficient weight to hold the short arm 15 raised, so that the two contact points 18 and 19, the former on the lever, and the latter in stationary position, are normally held apart. It will be readily seen, however, that when the mine car rides down the short end of the lever the points 18 and 19 are brought into 85 contact.

The apparatus is electrically controlled 90 from the single pole double throw switch 21. I arrange the negative wire 22 and the negative wire 23 of the respective magnets 11 and 12, in connection with the switch 21, 95 the wires being connected respectively to the points 24 and 25 of the switch. The line switch 26 is connected by wire 27 to the double throw switch 21, and by wire 28 it is connected to the contact point 18 of the lever 15. The two electromagnets are connected by the wire 29, and this wire 29 has connected thereto the wire 30 which is also connected to the stationary contact point 19. 100

In operation, the double throw switch 21 is controlled by an attendant, and as the parts are set in Fig. 1, a mining car may enter on the incoming track 1, and as the switch tongue 9 is not rigidly held, the 105 wheels of the car will pass through the 110

switch with slight obstruction. The mining car runs to the left in Fig. 1, until it rides down the lever 15 and brings the points 18 and 19 into contact. The circuit is now completed from the switch 26, wire 28, wire 30, wire 29, and either one of the selected magnets 11 or 12. If it is desired to shunt the car on the outgoing track 6, the switch 21 will be thrown to the point 25 and then a circuit will be closed from the wire 29, magnet 12, wire 23, point 25, switch 21, and wire 27 back to the switch 26. It may not be absolutely necessary that the switch 21 be thrown over to the point 25, but as a matter of precaution and absolute safety after the mining car runs through the switch on the incoming track, the switch 21 should be thrown to point 25, and in this way the energized electromagnet 12 positively throws the switch and holds it so that the car may now be shunted to the outgoing track 6. If it is desired the next incoming car may shunt to the same track 6. If, however, the next incoming car is to be shunted to the track 5, the switch 21 is thrown over to the point 24, then when the lever 15 is ridden down, the circuit is made from switch 26, wire 27, switch 21, wire 22, magnet 11, wire 29, wire 30, the contact points 19 and 18, and then wire 28 back to switch 26. The energized magnet 11 draws the switch tongue 7 over to the outgoing track 3', and then the track 5 is provided for the passage of the outgoing car.

From the above description taken in connection with my drawings, it will be seen

that the apparatus may be operated with facility, and that the cars may be shunted with accuracy and despatch, and that the invention in its physical embodiment possesses many meritorious and novel features to commend it as a practical and efficient device.

Having thus fully described my invention, what I claim as new and desire to secure by Letters Patent, is:—

1. In an electrically controlled switching mechanism, the combination with a straight track, a pair of divergent tracks, and a pair of switch tongues between the rails of the straight track, of an electromagnet at each side of the straight track having an armature connected to the switch tongue, a double throw switch controlling said magnets, and a weighted lever actuated by the movement of a car for closing the circuit to operate either of said switches.

2. In an electrically operated switching mechanism, the combination with three tracks, and intermediate double switching tongues, of electromagnets each having an armature linked to one of said tongues, a single pole double throw switch for operating selectively either of said magnets, and a circuit closer comprising a weighted lever to be operated by a passing car.

In testimony whereof I affix my signature in presence of two witnesses.

HINTON AUSTIN JACKSON.
